SMOKING PIPE

Timothy B. Powers, St. George, N. Y., assignor to
 Powers Smoking Pipes Corporation, New York,
 N. Y., a corporation of New York

Application May 31, 1934, Serial No. 728,337

16 Claims. (Cl. 131—12)

This invention relates to smoking pipes, and it is the primary object of the invention to provide improved closure means for the mouth of the pipe bowl slidably mounted upon the bowl whereby 5 the closure means is adjustable to open the pipe bowl to permit of filling tobacco therein and after the tobacco has been lighted adjusted to close the bowl mouth whereby the pipe with the tobacco therein may be placed in the pocket of the user, 10 in a drawer, or other places, and the tobacco and ashes will be retained in the pipe bowl and cannot escape from the pipe bowl into and soil the pocket of the user or any other place where the pipe may be placed, and in case the tobacco is 15 lighted with the possibility of burning the apparel or setting fire where the pipe may be placed by the burning tobacco spilling from the pipe bowl. The closure means also serves as a shield when the pipe is used outdoors, as by motorists, 20 golfers, fishermen, etc., to prevent the tobacco, ashes and sparks from the burning tobacco being blown from the pipe bowl, and the closure is readily adjusted whereby the mouth of the pipe bowl may be partly open to facilitate the proper burning and smoking of the tobacco.

A further object of the invention is to provide a smoking pipe having a novel arrangement of pipe bowl whereby the pipe may be set upon a horizontal surface without the possibility of the 30 pipe tipping over and spilling the tobacco or ashes therefrom by arranging the pipe bowl of circular form with the mouth extended into a peripheral portion of the bowl and the stem extended tangentially from the peripheral portion 35 of the bowl opposite the bowl mouth and arranged at the juncture thereof with the bowl with a flattened portion.

Another object of the invention is to provide a smoking pipe wherein the pipe bowl is arranged 40 externally with laterally extending projections in the form of ribs to increase the area of the outer surface of the bowl for dissipating the heat from the pipe bowl transmitted thereto from the burning tobacco and maintain the pipe bowl sufficiently cool to be grasped between the fingers or held in the hand without injury by the heat of the bowl.

Other objects and advantages will hereinafter appear.

50 In the drawing accompanying and forming a part of this application, Figure 1 is an elevational view looking at the top of the pipe.

Figure 2 is a side elevation with the mouth piece removed.

55 Figure 3 is a view taken on the line 3—3 of

Figure 2 looking in the direction of the arrows.

Figure 4 is a sectional fragmentary view of the pipe bowl, on an enlarged scale, taken on the line 4—4 of Figure 1 looking in the direction of the arrows to show the manner of securing the 60 closure mounting means on the pipe bowl.

Figure 5 is a sectional view taken on the line 5—5 of Figure 4 looking in the direction of the arrows.

Figure 6 is a perspective view, partly in section, of the means for mounting the closure upon the pipe bowl.

Figure 7 is a perspective view of the closure.

Figure 8 is a cross sectional view of the closure taken on the line 8—8 of Figure 7; and

Figure 9 is a perspective view of an abutment 70 mounted on the pipe bowl for limiting the closing movement of the closure.

In carrying out the embodiment of the invention illustrated in the drawing, the bowl 10 is 75 arranged in the form of a circular or cylindrical body provided with a chamber 11 extending diametrically of the bowl with the mouth opening through a peripheral portion of the bowl and a stem 12, integral with the bowl, extending tangentially of a peripheral portion of the wall of the bowl opposite the mouth of the bowl chamber and laterally from the bowl in angular relation to the mouth of the bowl chamber, and shown as extending substantially at a right angle 85 to the mouth of the bowl chamber, said stem having a bore therethrough communicating with the bowl chamber, and a mouth piece 13 removably connected to the stem in a conventional manner. At the juncture of the stem with the 90 bowl there is arranged a boss having a flattened surface to extend in the plane of a peripheral portion of the bowl as at 14, to serve as a base to engage and support the pipe upon a horizontal surface with the mouth of the bowl chamber 95 uppermost and prevent the spilling of tobacco and ashes from the bowl chamber. To permit of the placing of the pipe in the pocket of the apparel of the user with part of the tobacco which has not been consumed in the pipe bowl, 100 or with the tobacco lighted, and preventing the soiling or burning of the pocket by the tobacco or tobacco ash spilling from the bowl chamber, or when placed elsewhere, as in a drawer with the possibility of starting a fire, adjustable 105 closure means is provided for the mouth of the bowl chamber, comprising a plate 15 bifurcated at one end, as at 16, and arranged to arcuate shape in longitudinal section to conform to the curvature of the periphery of the pipe bowl,

110

said plate being slidably mounted on the pipe bowl to have adjustment in a direction toward and the legs of the bifurcation straddling the pipe stem to uncover the mouth of the bowl chamber and in a direction away from the pipe stem to cover the mouth of the bowl chamber.

Means are provided to slidably mount and yieldingly hold the closure plate on the pipe bowl and guide the closure plate at the opposite sides and in the embodiment shown as comprising plates formed to angle shape in cross section, as shown in Figure 6, the one angle portion 17 being arranged to arcuate shape in longitudinal section to conform to the curvature of the periphery of the pipe bowl, the other angle portions 18 of said members having an edge of arcuate form and adapted to be engaged in parallel slits or recesses 19 of like shape arranged in the pipe bowl as by a circular saw, the depth of said recesses or saw cuts being slightly less than the width of the angle portion 18 so that the angle portion 17 will be spaced from the pipe bowl a distance slightly greater than the thickness of the closure plate 15. The closure plate is of a width slightly greater than the diameter of the bowl chamber, and the recesses 19 are spaced apart a distance so that the opposite side marginal portions of the closure plate will move freely relative to the angle portions 18, and said angle portions 18 guiding and positioning the closure member relative to the mouth of the bowl chamber, as clearly shown in Figures 1 and 3. To yieldingly retain the closure member either in position to cover and close the mouth to the bowl chamber, as shown in Figure 2, or partially cover the same, or in mouth uncovering position, as shown in Figures 1 and 3, the mounting members for the closure plate are made of resilient material and the angle portion 17 is partially separated from the angle portion 18 by a slit 20 extended inward from one end to arrange the one end of said angle portion 17 as a yielding tongue, as shown at 17' in Figure 6, and said tongue is deflected slightly inward in the direction of the portion 18 to restrict the space between said tongue of the angle portion 17 and the pipe bowl to yieldingly and frictionally engage the portion of the closure plate interposed between said tongue 17' and the pipe bowl and thus hold the closure plate in any of its adjusted positions. In the position of the closure plate uncovering the mouth of the bowl chamber, the bifurcation legs engage at opposite sides of the pipe stem and the pipe stem limiting the uncovering movement of the closure plate. To limit the mouth closing movement of the closure plate, an abutment 21 is mounted in the pipe bowl for the engagement of the end of the closure plate opposite the bifurcated end, said abutment, as shown in Figure 9, being formed from a rod with the ends bent at a right angle and adapted to engage in recesses in the pipe bowl.

To secure the closure plate mounting members against withdrawal from the recesses 19, lips 22 are stamped from and deflected laterally of the angle portions 18, the lips being arranged whereby as the angle portions 18 are inserted into the recesses 19 the lips will be sprung inward, but as the inherent tendency of the material is to move said tongues laterally they will bite into the wall of the recess by any movement of the angle portions 18 outward from the recesses 19 and thus prevent the withdrawal thereof from said recesses.

In the use of smoking pipes, there is an accumulation of burnt products about the mouth of the pipe bowl and this accumulation may be such as to frictionally resist and interfere with the ready and easy adjustment of the closure plate should the entire surface of the mouth closing portion of the plate contact with the pipe bowl. To obviate this and reduce the contact of the closure plate with the bowl to a minimum frictional engagement with the pipe bowl, this portion of the plate is depressed, as at 23, to extend outwardly from the pipe bowl and whereby only the portions bounding said depressed portion 23 will engage with the pipe bowl. To facilitate the adjusting of the closure plate the closure plate is provided with a finger or finger nail engaging portion shown as a nib 24 pressed outwardly from the depressed portion 23 which may be readily engaged by the nail of the thumb or finger.

It is well known due to the burning of the tobacco in smoking pipes the pipe bowl is heated to such a high temperature that should the pipe bowl be grasped by the hand of the user it may result in injury. To effect a quick dissipation of the heat from and cooling of the pipe bowl whereby it may be readily engaged by the fingers or hand without injury thereto, the outer surface area of the pipe bowl is increased. This is effected by arranging the outer surface of the pipe bowl with laterally extending projections, and in the embodiment shown comprising concentric ribs 25 extending outwardly from the opposite ends of the pipe bowl, and the peripheral portion of the bowl opposite that engaged by the closure plate may also be provided with outwardly extending ribs.

Having thus described my invention, I claim:

1. In a smoking pipe, a cylindrical bowl having a chamber extending diametrically thereof, the mouth of which opens through the peripheral wall of the bowl and an integral stem extending tangentially of a portion of the peripheral wall of the bowl in angular relation to the mouth of the bowl chamber and having a bore communicating with the bowl chamber, a closure plate for the mouth bowl of arcuate shape in longitudinal section to conform to the curvature of the peripheral wall of the bowl and of a width greater than the cross sectional area of the bowl chamber, and means secured to the bowl to guide the plate at the opposite sides and yieldingly hold the plate to the bowl to permit of sliding adjustment of the plate about the peripheral wall of the bowl to cover and uncover the mouth of the bowl chamber and retain the plate in adjusted position.

2. A smoking pipe as claimed in claim 1, where in the means to yieldingly hold the plate to and guide the plate on the bowl is mounted on the bowl intermediate the mouth of the bowl chamber and stem, and the plate is arranged with a bifurcation at one end to be opposed to the stem when the plate is mounted on the pipe bowl and adapted to straddle the stem in the mouth opening position of the plate and said stem being adapted to limit said movement of the plate, and an abutment secured in the bowl to limit the mouth closing movement of the plate.

3. In a smoking pipe, a bowl of cylindrical form having a chamber therein the mouth of which opens through the peripheral wall, a pair of angular members mounted by engaging one angle portion in slits in the bowl which are spaced apart a distance greater than the width of the bowl chamber, the other angle portion of said members spaced from the bowl and extending inward to-

ward each other, and an arcuate plate slidably engaging between the bowl and angle portion of said members spaced from the bowl and adapted to be adjusted to cover and uncover the mouth of the bowl chamber.

5. In a smoking pipe, a bowl of cylindrical form having a chamber the mouth of which opens through the peripheral wall, said bowl having parallel slits therein spaced apart a distance greater than the width of and disposed at one side of the mouth of the bowl chamber, a member of angle form in cross section mounted on the bowl by engaging one angle portion in each slit with the other angle portion arranged as a resilient tongue and extending inward in juxtaposed relation to the peripheral wall of the bowl, and an arcuate plate slidably engaged on the opposite marginal portions between the bowl and the resilient tongues of said members to have adjustment to cover and uncover the mouth of the bowl chamber and the resilient tongues of said members being adapted to retain the plate in adjusted positions.

5. In a smoking pipe, a cylindrical bowl with the mouth of the chamber opening through the peripheral wall and a stem extended from the peripheral wall at substantially a right angle to the mouth of the bowl chamber and having slits in the peripheral wall intermediate the stem and mouth of the chamber spaced apart a distance greater than the width of the mouth of the chamber, a member of angle shape in cross section mounted on the bowl by engaging one angle portion in each slit and the other angle portion arranged as a resilient tongue extended inward and juxtaposed to the bowl, and an arcuate plate having a bifurcated end slidably engaged between said members with the bifurcated end opposed to the stem and the tongues engaged over the opposite sides of the plate to have adjustment to cover and uncover the mouth of the bowl chamber, and the bifurcation legs adapted to straddle the stem when the plate is adjusted to uncover the mouth of the bowl chamber.

5. A smoking pipe as claimed in claim 5, wherein in the portion of the angle members engaged in the slits have nibs stamped therefrom normally sprung laterally and adapted to be sprung inward when engaged in the slits and bite into the wall by movement outward from the slits to secure said angle portion of the members against withdrawal from the slits.

55

60

65

70

75

7. A smoking pipe as claimed in claim 5, wherein in the plate is arranged with a depressed portion to extend outward from the bowl when the plate is mounted thereon to reduce the engagement of the plate with the bowl and frictional resistance to the adjustment of the plate.

8. A tobacco pipe consisting of a single block of suitable material including a bowl portion of cylindrical shape having its axis substantially horizontal when in normal smoking position, said bowl portion having a cavity extending downwardly from the upper part thereof in said normal position, said block of material further including a stem extending from the lower part of the bowl and having a suction passage communicating with the lower part of the bowl, and bifurcated means slidable around the cylindrical periphery of the bowl portion of said pipe to prevent accidental dispersal of ashes and tobacco from said cavity, said means having a portion limiting the movement of said bifurcated means.

9. A tobacco pipe consisting of a single block of suitable material arranged with a bowl portion of cylindrical shape having a chamber extending diametrically thereof the mouth of which chamber opens through the peripheral wall of the bowl with a stem extended from a point at the bottom of the bowl substantially diametrically opposite the mouth of the bowl chamber and midway between the sides of the bowl, said stem having a flat bottom face under the bowl extending tangential to the peripheral wall of the bowl adapted to prevent the pipe tipping over when set upon a horizontal surface, and said stem having a suction passage communicating with the bottom of the bowl chamber.

10. In a smoking pipe, a cylindrical bowl having a chamber extending diametrically thereof the mouth of which opens through the peripheral wall of the bowl and an integral stem extending tangentially of a portion of the peripheral wall of the bowl having a bore communicating with the bowl chamber, and a closure plate of arcuate form in longitudinal section to conform to the peripheral wall of the bowl slidably mounted on the peripheral wall of the bowl intermediate the mouth of the bowl chamber and stem to be moved to position to cover and uncover the mouth of the bowl chamber, and said plate having a bifurcation at the end opposed to the stem adapted to straddle the stem when the plate is adjusted to uncover the mouth of the bowl chamber.
